CLAIM

The ornamental design for a nut locking assembly comprised of a nut and a locking washer, as shown and described.

DESCRIPTION

FIG. 1 is a perspective view of a nut locking assembly comprised of a nut and a locking washer showing my new design;

FIG. 2 is a perspective view of the nut of a nut locking assembly shown removed from the locking washer;

FIG. 3 is a front elevation view of FIG. 2;

FIG. 4 is a rear elevation view of FIG. 2;

FIG. 5 is a left side elevation view of FIG. 2;

FIG. 6 is a right side elevation view of FIG. 2;

FIG. 7 is a top plan view of FIG. 2;

FIG. 8 is a bottom plan view of FIG. 2;

FIG. 9 is a cross-section view of the nut as taken along line 1-1 in FIG. 3;

FIG. 10 is a front elevation view of the locking washer of the nut locking assembly shown removed from the nut;

FIG. 11 is a rear elevation view of FIG. 10;

FIG. 12 is a left side elevation view of FIG. 10;

FIG. 13 is a right side elevation view of FIG. 10;

FIG. 14 is a top plan view of FIG. 10; and,

FIG. 15 is a bottom plan view of FIG. 10.

The broken lines depict environment only and form no part of the claimed design.

1 Claim, 15 Drawing Sheets
